UNITED STATES PATENT OFFICE

ISIDOR GRABER, OF MILWAUKEE, WISCONSIN

DESIGN FOR A CAP

Application filed December 6, 1930. Serial No. 37,900. Term of patent 3½ years.

To all whom it may concern:

Be it known that I, ISIDOR GRABER, a citizen of the United States, residing at Milwaukee, in the county of Milwaukee and State of Wisconsin, have invented a new, original, and ornamental Design for Caps, of which the following is a specification, reference being had to the accompanying drawings, forming part thereof.

Fig. 1 is a perspective of the cap showing my new design.

Fig. 2 is another perspective of the cap showing my new design.

Fig. 3 is a front elevation of the same.

I claim:

The ornamental design for a cap as shown. In testimony whereof I affix my signature at Milwaukee, Wisconsin.

ISIDOR GRABER.
